UNITED STATES PATENT OFFICE.

MAX DWORK, OF BROOKLYN, NEW YORK.

WINDOW SCAFFOLD.

Application filed October 31, 1922. Serial No. 598,147.

To all whom it may concern:

Be it known that I, MAX DWORK, a citizen of the United States, and a resident of Brooklyn, in the county of Kings and State of New York, have invented certain new and useful Improvements in Window Scaffolds, of which the following is a specification.

This invention relates to devices adapted for use in connection with window cleaning and has for its object the provision of a safe and reliable support for persons employed in dangerous tasks such as cleaning the outside of windows and where it is necessary for such persons to place themselves beyond the outer wall of the building.

A further object of the invention is the provision of a support which furnishes not only a comfortable seat for a person employed in dangerous tasks and sufficient room for conveniently holding articles and implements intended for use in the occupation, but a safeguard against accidental precipitation from the support.

Another object of the invention is the provision of a device of such a character that the same may be folded into a small and compact unit for storage or transportation and which may be readily set up and applied to a window in a short space of time.

Other objects and advantages will become apparent during the course of the following description.

The invention is illustrated by way of example in the accompanying drawings, in which,

Figure 1 is a view in perspective of my improved scaffold applied to a window frame.

Figure 2 is a transverse vertical section of the scaffold.

Figure 3 is a view in perspective of the scaffold folded into a neat and compact unit, showing one of the locking pins detached from its holder.

Figure 4 is a fragmentary view in section disclosing the adjustable supports for the seat.

Figure 5 is a transverse section of the supporting rod adapted to engage the window frame disclosing the means for adjusting the ends of the rod.

Referring to the drawings, the letter A designates the seat, B the back and C the foot rest. The seat A is composed of

spaced parallel bars 1, 2 and 3 equipped with a plurality of spaced slats 3a. Upon the outer ends of the bars 1, 2 and 3 is mounted a rod 4, the ends of the bars being turned as at 5 to form sockets for said rod.

Pivotedly connected at their lower ends to the rod 4 are bars 6 and 7 which are equipped with a plurality of spaced slats 8, the slats being rigidly secured to said bars. The upper ends of the bars 6 and 7 are provided with sockets 9 to receive a rod 10.

Rigidly secured to the outer ends of the bars 1, 2 and 3 are stops 11 which are located in the path of the rocking bars 6 and 7 to prevent accidental forward movement of the back B upon the seat A when the scaffold is located in an operative position with respect to a window frame. The seat A is adapted to rest upon the sill 12 of a frame 13 with the side edges of the seat located between the vertical side members of the frame.

A rod 14 is mounted upon the forward end of the bars 1, 2 and 3 with the forward ends of the bars being turned to provide sockets for supporting said rod. The rod 14 is hollow and is adapted to receive the headed adjustable rods 15 and 16 which are slidable within the rod 14 and held in place by means of set screws 17. The slidable rods 15 and 16 are adapted to engage the inner edges of the window frame 13 for maintaining the seat upon the sill 12 and preventing slippage of the seat from said sill. Pivotedly connected to the rod 14 are bars 18 and 19 which are equipped with spaced slats 20. The lower ends of the bars 18 and 19 are turned outwardly at right angles as shown at 21. Upon the upturned portions 21 is secured a slat 22 which is spaced from the lower slat 20 of the foot rest C as shown in Figure 1. The upper ends of the bars 18 and 19 are offset from the plane of said bars for a purpose which will be presently described in connection with the folding of the scaffold into a neatly packed unit.

Guides 23 are rigidly secured to the bars 1, and 2 and project laterally from the sides of the seat A and are adapted to slidably receive a brace 24 for each guide. The braces 24 are provided with teeth 25 along one longitudinal edge and with teeth 26 along the other longitudinal edge but ex-

tended in a direction which is opposite to the direction of extension of the teeth 25 so that when the brace is located within the guide 23 the teeth 25 will engage the inner edge 27 of the guide while the teeth 26 will engage the rear edge 28 of said guide whereby the brace 24 will be held in rigid position when the lower reinforced end 29 of said brace is in engagement with the outer wall 30 of a building. A set screw 31 mounted in the guide 23 is adapted to engage the brace 24 and lock said brace in position.

A chain 32 is connected with each of the bars 6 and 7 and provided with a ring 33 adapted to be slipped on the rod 14. The set screws 17, which provide means for securing the rods 15 and 16 in any of their adjusted positions will prevent slipping or accidental disengagement of the rings 33 from the rod 14.

Chains 34 are provided with rings 35 which are slipped on the rod 10 and are provided with a link 36 at their inner ends adapted to engage with a hook 37 secured in the outer edges of the window frame 13. Chains 38 are secured to the bars 6 and 7 and are extended upwardly and connected with the chains 34 for strengthening the connection between the upper end of the seat A and the window-frame 13. A chain 39, which is loosely swung between the pair of chains 34, is provided with rings 40 which are for the purpose of supporting cloths and which are conveniently located in front of the person cleaning the window. The chains 39 may be employed for the purpose of supporting a bucket filled with proper cleaning fluid.

40 When the scaffold has been removed from the window it may be folded into a neat and compact unit as shown in Figure 3 with the back B folded in the direction indicated by the arrow in Figure 2 so that the back 45 of the seat is located in face to face engagement with the under side of the seat A. The offset portion 41 of the bars 18 and 19 of the foot rest C will permit the foot rest C to be folded in substantially face to face engagement with the upper face of the seat A.

50 The braces 24, as shown more particularly in Figure 4, by reason of their place in the guides 23 may be moved to a horizontal position and aligned with the side edges 55 of the seat A. The scaffold, when folded in this manner, makes a compact and unitary structure for storage and transportation purposes.

While I have herein shown and described 60 the preferred form of my invention, it is to be understood that various changes and modifications may be made herein without departing from the spirit of the invention or the spirit and scope of the appended 65 claims.

What I claim as new is:

1. A device of the character described comprising a seat adapted to be supported on a sill of a window frame, a back pivotally connected to a longitudinal edge of the seat, a rod having extensible ends engageable with the inner edges of the frame, mounted on the other longitudinal edge of the seat, a foot rest pivotally mounted on the rod, depending from the rod, and adapted to engage the wall of a room below the window sill, chains secured to the back and adapted to be connected with the window frame, chains connecting the back with the rod on the seat, said chains and rod cooperating to hold the back and seat on the window frame, braces adjustably mounted on the seat and engageable with the wall of a building for aiding in supporting the seat, and means connecting certain of the chains for supporting implements.

2. A device of the character described comprising a seat adapted to be supported on the sill of a window frame, a back pivotally connected to the seat, a foot rest pivotally connected to said seat, means on the inner end of the seat adapted to engage the inner edges of the window frame, and means secured to the back and adapted to be connected with the window frame, and adjustable means slidably connected with the seat and engageable with the wall of a building for aiding in supporting the seat.

3. A device of the character described comprising a scaffold adapted to be removably mounted on a sill of a window frame, comprising a seat adapted to rest on the sill, a back pivotally connected with the seat, a plurality of chains secured to the back and adapted to be connected with the window frame, means on the inner edge of the seat engageable with the inner edges of the window frame for maintaining the seat on the sill, a foot rest depending from the inner end of the seat and embracing the inner edge of the sill of the window frame, and braces slidably mounted on the seat and having free ends projecting inwardly from said seat adapted to engage the wall of a building.

4. A window scaffold comprising a seat adapted to be supported on a sill of a window frame, a back pivotally connected with the seat, chains secured to the back and adapted to be connected with the window frame, and means on the inner edge of the seat engaging the window frame and cooperating with the chains for maintaining the seat in position on the sill, guides projecting laterally from the seat, brace bars slidably mounted in the guides and provided with oppositely disposed teeth along their opposite edges, the oppositely disposed teeth being adapted to engage opposite edges of the guide, and means for locking the braces

115

in adjusted position within the guide, the inner ends of the braces being adapted to engage the outer wall of a building.

5. A foldable window scaffold comprising a seat adapted to be supported on the sill of a window frame, a back pivotally connected to a longitudinal side edge of the seat, a foot rest pivotally connected with the other longitudinal side edge of the seat, 10 means adapted to engage the inner edge of the window frame for preventing slippage

of the seat from the sill, means secured to the back and adapted to be connected with the window frame, and bracing means adjustably connected with the seat adapted to engage the wall of a building, said back being foldable upon the seat with the rear face of the back in face to face engagement with the under side of the seat, with the foot rest foldable upon the upper face of the seat. 15

MAX DWORK.
